WHEEL CENTER

Donald J. Reid, Pleasant Ridge, Mich., assignor to Kelsey-Hayes Company, Romulus, Mich.

Filed Oct. 2, 1972, Ser. No. 294,490

Term of patent 14 years

Int. Cl. D12—16
U.S. Cl. D12—211

FIG. 1 is a side elevational view of a wheel center showing my new design.

FIG. 2 is a cross-sectional view of the wheel center taken along the line 2—2 of FIG. 1.

FIG. 3 is a cross-sectional view taken along the line 3—3 of FIG. 2.

FIG. 4 is a perspective view.

The rim of the associated wheel is shown in dotted lines in Figure 2 to indicate the environment in which the invention is used.

I claim:

The ornamental design for a wheel center, substantially as shown and described.
